UNITED STATES PATENT OFFICE.

JOHN PEARSON, OF CHICAGO, ILLINOIS, ASSIGNOR TO THE PULLMAN COMPANY, OF CHICAGO, ILLINOIS, A CORPORATION OF ILLINOIS.

CAR-FRAMING.

1,010,684.

Specification of Letters Patent.

Patented Dec. 5. 1911.

Application filed July 18, 1910. Serial No. 572,563.

To all whom it may concern:

Be it known that I, JOHN PEARSON, a citizen of the United States, residing at Chicago, in the county of Cook and State of Illinois, have invented certain new and useful Improvements in Car-Framing, of which the following is a specification.

My invention pertains to improvements in the superstructure of railway cars and pertains more particularly to the framing of box freight cars, although the application of the invention is not restricted to such particular use.

One of the objects of the invention is the production of a framing of this character which shall be simple in structure, economical to manufacture, and the parts of which may be assembled with facility and despatch.

Obviously, another object of the invention is the provision of a car framing of this kind with adequate strength and rigidity.

In the accompanying drawings, which form a part of this specification, I have illustrated one desirable embodiment of the invention and in these drawings, Figure 1 is a fragmentary perspective view of the metallic framing of the car body; Fig. 2 is a fragmentary central longitudinal vertical section through a car of this kind showing particularly the framing with many parts omitted; Fig. 3 is a cross-section through the frame; Fig. 4 is a fragmentary perspective detail of the attachment of the side posts to the side sill; Fig. 5 is an enlarged section showing the manner of securing the combined belt rail and grain strip to the side sill; Fig. 6 is an enlarged fragmentary vertical transverse section showing a portion of the bolster, the side sill, and one of the vertical posts; and Fig. 7 is a fragmentary vertical longitudinal section through the end portion of the car illustrating the manner of supporting the ends of the intermediate sills by the end sill.

Referring to the drawings, it will be apparent that the car has body bolsters 10, the ends 11 of which extend upwardly beyond the main portion of the bolster, the latter being equipped with flanges 12 extending completely around the same. The channel center sills 13, 13 are supported on seats or brackets 14, 14 forming integral parts of the bolsters. At each side of the car I employ an angle side sill 15 resting upon the

upstanding portions 11 of the bolsters, and secured by rivets at 16 to the flanges 12 of the latter, the depending flanges of the side sills lying outside of and bearing directly against the ends of the bolsters. The angle side sills at intervals are apertured or pierced, at 17 for the accommodation of the lower offset ends 18 of the channel posts 19, some of which are vertically disposed while others are inclined as is clearly indicated. 60 The webs of the lower ends 18 of these posts rest directly against the inner faces of the depending flanges of the side sills, being riveted thereto at 20, as is shown clearly in Fig. 6. At the top of the framing I provide 70 two longitudinal Z-bars arranged with their webs 22 disposed horizontally and with their outer and inner flanges 23 and 24 disposed vertically. The upper ends of the posts 19 are riveted to the depending flanges 75 23 of these Z-bars and to suitable gusset or brace plates 25 positioned between the posts and the flanges 23, as is clearly shown, for example in Figs. 2 and 3.

At the corners of the car I provide upright angle posts 26 riveted at 27 to the outer faces of the angle side sills 15 and to the outer faces of the upstanding flanges 28 of the angle end sills 29, the horizontal inwardly extended flanges of which rest upon 80 and are riveted to the end portions of the angle side sills, all as is clearly shown in Fig. 1. At their center portions these end sills 29 are supported on the center sills 13 by means of a Z-bar 29^a shown in Fig. 2. 90 At its top end each of these corner posts is disposed outside of the flange 23 of the corresponding longitudinal bar and is riveted thereto at 30. The companion flange of the corner post is riveted at 31 to the downwardly extended flange 32 of an angle end carline or roof support 33, the horizontal flange of which is beneath and riveted to the web 22 of the longitudinal bar at 34. This construction provides an unusually simple 95 and rigid structure at this portion of the car frame. Any suitable form of intermediate carlines 35, 35, may be employed, and although I have shown in the drawings a desirable form and style of the same, the 105 invention is in no way restricted or limited to the character of such parts of the framing. At the end of the car the end sill 29 and the end carline 33 are connected together by suitable end posts 36, 36, which 110

may be of any desirable form but in the present instance are angle-shaped in cross-section.

The floor 37 is supported on intermediate 5 wooden sills 38, 38, the ends of which are supported by the end sills by means of suitable brackets 39 riveted to the bottom faces of the horizontal flanges of the end sills and provided with suitable shelves or ledges for 10 the ends of the intermediate sills whereby the latter are suitably held in place and properly supported.

As is customary in cars of this kind, the same is provided with inner and outer 15 sheathing a part of which is shown in Fig. 2, and in order to supply a convenient means for the application of such sheathing and the ready discharge of grain which may leak between the sheathing, I fasten by 20 means of bolts 40 combined belt rails and grain strips 41 to the top inturned flanges of the side sills 15, the top faces 42 of such grain strips being inwardly beveled for the obvious purpose of discharging the grain 25 to the interior of the car. The floor 37 may, if desired, be overlapped slightly by such grain strip as I have indicated in Fig. 5. Much the same construction is employed at 30 the ends of the car with the changes necessary owing to the differences in construction of the metal framing. Whereas I have herein shown other parts of the car construction they form no portion of the present invention and need no detailed description.

The bolster herein illustrated forms the subject matter of another co-pending application Serial Number 567,862, filed June 35 20, 1910.

The above should be sufficient for a full

and complete understanding of the present 40 invention which resides in the structure of the car framing and the advantages of this particular arrangement and combination of parts will be readily apparent to those skilled in the art. It should be obvious that 45 a framing of this character is economical of production, possesses great rigidity and is easily assembled.

I claim:

1. In a car body frame, the combination 50 of an upright angle corner post, an angle end carline having one flange disposed vertically and secured to one of the flanges of said corner post against its inner face and a ton Z-bar disposed longitudinally of the car 55 and having its web arranged horizontally and riveted to the top of the companion flange of said end carline, said top bar having a depending flange disposed inside of and fastened to the other flange of the corner angle post, substantially as described.

2. In a car body frame, the combination 60 of angle side sills each having one flange disposed horizontally and its companion flange depending vertically therefrom at its outer edge, an angle end sill having its horizontal flange resting at its ends upon and secured to the horizontal flanges of said side sills and having an upstanding vertical flange along its outer edge, and angle corner 65 posts disposed outside of said sills and secured to the vertical flanges of both the side and end sills, substantially as described.

JOHN PEARSON.
